UNITED STATES PATENT OFFICE.

ALFRED H. HUMPHREY, OF NEW YORK, N. Y., ASSIGNOR TO GENERAL GAS LIGHT COMPANY, OF KALAMAZOO, MICHIGAN.

DESIGN FOR A GAS-LAMP.

43,001.

Specification for Design.

Patented Sept. 10, 1912.

Application filed June 20, 1912. Serial No. 704,929. Term of patent 14 years.

To all whom it may concern:

Be it known that I, ALFRED H. HUMPHREY, a citizen of the United States, residing at the city of New York, in the county of New York and State of New York, have invented a new, original, and ornamental Design for a Gas-Lamp.

My new, original and ornamental design for a gas lamp is clearly illustrated in the

accompanying drawing, in which the design is shown in elevation.

I claim:

The ornamental design for a gas lamp as shown.

ALFRED H. HUMPHREY.

Witnesses:

G. A. HUMPHREY,
KATE A. HUMPHREY.
